KNITTING MACHINE

John Edward Lynam, Mapperley, and Patrick Gideon McCarthy, Loughborough, England, assignors to William Cotton Limited, Loughborough, Leicestershire, England

Application January 8, 1949, Serial No. 69,864

Claims priority, application Great Britain April 28, 1947

5 Claims. (Cl. 66—157)

1

This invention concerns knitting machines, especially Cotton's patent and other straight bar knitting machines. In such machines it is customary to provide instruments which for certain operations, during which the normal knitting movements of the needles are modified, are moved to occupy temporarily a position in which they co-operate with the needles. Examples of such instruments are the transfer points employed for fashioning and for producing a picot edge and like purposes, the welt hooks or other welting instruments employed in automatic welt turning apparatus, needle-deflecting instruments, and instruments for pressing selected needles or for causing selected needles to mispress. It is essential that such instruments shall be returned from their temporary attitude before the needles revert to their normal knitting motions otherwise the certainty arises that the needles will be smashed or damaged. The machine is timed to avoid such a mishap, but on the other hand since some of the machine movements are produced by springs (e. g. that hold cam followers against cams) there is always the danger that the required movements will not in fact be produced. It is this danger that the invention seeks to overcome or to minimise.

The invention therefore provides in a knitting machine, especially a Cotton's patent or other straight bar knitting machine, having instruments movable to occupy, for a period during which the normal knitting cycle of the machine is modified, a temporary attitude in which they co-operate with the needles or other knitting elements; a stop motion including apparatus for detecting failure of said instruments to revert from that attitude preparatory to or upon resumption of the normal knitting cycle, and/or for detecting failure of the needles or other elements to enter upon modified motions preparatory to or upon said instruments assuming said temporary attitude. It is to be explained that the expression "stop motion" as employed herein in the same broad sense that it is used in the trade, to include not only a motion (i. e. mechanism or apparatus) whereby the machine is actually brought to rest but also a motion whereby knitting operations or at least certain of them are suspended with a view to avoiding the ill effects that would otherwise accrue from the fault thus detected: furthermore, the expression "failure" is employed in a broad sense to include incipient failure.

The invention further includes the provision in a knitting machine having at least one part

5 movable to occupy, for a period during which the normal cyclic motions imparted to knitting elements of the machine are modified, a temporary attitude in which it would be fouled by said elements were they to pursue their normal motions, a stop motion including means responsive to a relative mispositioning of said part and elements at the beginning or end of said period.

10 The invention is primarily but not exclusively concerned with the machine forming the subject of Patent No. 2,428,514. The patent provides in a Cotton's patent or other straight bar knitting machines, welt turning mechanism of the kind wherein welting instruments (or welt hooks) 15 are inserted from the plain side of the needles to receive thread or thread kinks of an initial welt course, are retracted from the needles during the knitting of at least a portion of the welt, are subsequently advanced to offer the initial 20 welt course held by them to be transfixed by the rising needles, and are disengaged from the transfixed course by retraction; characterised by supports for engaging the initial course at least in the neighbourhood of the selvedge, and means 25 for lifting said supports in relation to the welting instruments to facilitate the retraction of the latter from the transfixed initial course. These supports are constituted by instruments that register with and move upwards with the 30 needles and they also serve to deflect spaced needles out of alignment with the rest in the restoration of the initial course of welt. It will therefore readily be appreciated that the normal needle motions require to be modified while the 35 supports are in operation and that the supports must be returned to an operative position before the needles assume their normal motions otherwise a smash-up will result.

30 The above and other features of the invention are set forth in the appended claims and are disclosed in the detailed description given by way of example, of the particular embodiment 40 illustrated in the accompanying drawings in which:

45 Figure 1 is a diagrammatical view of certain of the mechanism provided by Patent No. 2,428,514 together with electrical apparatus according to the present invention.

Figure 2 is a general cross sectional view of 50 a machine incorporating apparatus according to this invention.

Figure 3 is a detail sectional view of auxiliary pressing mechanism incorporating a switch device.

Figure 4 is a front view of part of Figure 3.

2

Figures 5 and 6 are front and side views respectively of a switch device for association with needle bar pressing mechanism.

Figures 7 and 8 are front and side views respectively of a switch device for association with control mechanism for knocking-over bits.

Figure 9 is a circuit diagram showing a modified arrangement.

In the specific embodiment described in the aforesaid patent and partly illustrated in Figures 2, 3 and 4 of the accompanying drawings, the support instruments 1 are carried by an instrument bar 2 which is mounted on the knocking-over bar 3 and is capable of being raised on the latter. Each support instrument constitutes an auxiliary presser and is formed with a loop-engaging support ledge or shoulder. In the operation of turning the welt (i. e. restoring the initial welt course to the needles) the needle bar pressing truck 4 is shogged from the normal pressing cam 5 on to an auxiliary pressing cam 6 so as to modify the pressing movements of the needles 7. The knocking-over truck 8 is likewise shifted from the normal knocking-over cam 9 to an auxiliary cam 10 so as to modify the normal movement of the knocking-over bits 11 and to advance the knocking-over bar 3 together with the auxiliary pressers 1, so that the needles 7 are capable of pressing against said pressers instead of against the normal press-edge. These two trucks 4, 8, are shogged positively by means of truck-shogging bars 12, 13, respectively operated by truck levers 14, 15, and timing studs on a timing chain or any other patterning device. They are returned in the opposite direction by springs 55, 66, respectively (Figure 1), when the machine resumes its normal knitting motions. Truck 4 and its bar 12 constitute a change-over device movable in one direction to produce the change-over from the normal knitting cycle and in the reverse direction to produce the reverse change.

After every second needle 7 has been engaged with the associated auxiliary presser 1 so that its beard is pressed and so that the said needle is deflected towards the front of the machine out of alignment with the other needles, the auxiliary pressures rise when the needles transfix the loops offered to them by the welt hooks 16. In this upward movement of the auxiliary pressures 1 and the needles 7 the welt loops are engaged by the ledges on the auxiliary pressers and are lifted, thereby permitting the welt hooks 16 to be disengaged from said loops by a sharp retractive movement. The auxiliary pressers 1 are caused to rise with the needles 7 by being themselves raised on the knocking-over bar 3. This movement is produced by a bar 17 (Figures 3 and 4) slidable lengthwise of the knocking-over bar, and in order to shift this bar 17 a truck 18 is shogged into engagement with a mis-pressing cam 19 by means of a truck-shogging rod 20 operated by a truck lever 21 and a stud on the timing chain, (or other patterning device), said truck-shogging rod 20 being returned in the opposite direction by a return spring 121 (Figure 1). Thus, a control device is provided comprising the bar 17, bell crank 38, rod 39, spring 40, truck lever 140, truck 18, rod 20 and truck lever 21, which parts are movable in one sense to produce movements of the instruments 1 so that they occupy, for a period during which the needles perform their modified cycle of movements, a temporary attitude in which they cooperate with said needles, and in the reverse sense to pro-

duce movement of the instruments out of that attitude.

Since the return of the auxiliary pressers to their inoperative position is under control of the spring 121 just mentioned it will be understood that there is a danger that this spring may prove insufficient for the purpose required and that the auxiliary pressers 1 will remain in their raised position when the needles 7 revert to their normal knitting motions. In such an eventuality the beards of the needles 7 would catch the ledges of the auxiliary pressers 1 and would be smashed. In order to prevent this mishap the following apparatus is provided by the present invention comprising a stop motion which includes means responsive to incorrect relative movement between the change over device and the control device, for stopping the machine.

An electric motor 23 (Figure 2) which drives the machine is controlled by a circuit that includes not only a switch 24 capable of being broken automatically by means of a timing chain or equivalent device 25 but also a second switch (or relay switch) 26 operative by a relay circuit 27 (Figure 1) so that when this relay circuit is energised the second switch 26 is broken and the motor 23 and knitting machine brought to a standstill. Incidentally, operation of this second switch 26 may serve to complete a subsidiary circuit that includes a telltale lamp 28. The relay circuit 27 includes a switch 29 (see also Figures 3 and 4) which is normally open but which is closed when the mis-pressing truck 18 is shogged to raise the auxiliary pressure; for convenience this switch 29 is referred to as the mis-pressing switch 29. It also includes two other switches 30, 31 that are themselves arranged in parallel and are normally closed. These two switches consist of a switch 30 (see also Figures 5, 6) which is opened when the truck 4 for the pressing movements of the needle bar is shogged to its auxiliary cam 6 (and therefore, for convenience, called the needle pressing switch 30) and a switch 31 which is opened when the truck 8 for the knock-over bar is shogged to its auxiliary cam 10 (and therefore, for convenience, called the knock-over switch 31).

The sequence of operations is as follows:

- 50 1. Press rod 12 shogs to modify the pressing movements imparted to the needles 7 and to open needle pressing switch 30.
- 55 2. Knock-over rod 13 shogs to modify the movement of the knocking-over bits 11 and to open knock-over switch 31.
- 60 3. Mis-pressing rod 20 shogs to bring the auxiliary pressers 1 into operation and to close mis-pressing switch 29.

At this phase, then the relay circuit 27 is open but it will be appreciated that if the timing or control mechanism which results in the pressing motions of the needle bar being modified preparatory to the auxiliary pressers being brought into operation, should fail, the pressing switch 30 will remain closed with the further result that upon the mis-pressing switch 29 being closed as the auxiliary pressers 1 are brought into operation the relay circuit 27 will be completed and the machine brought to a standstill. This will obviate the smash-up that would unavoidably result were the auxiliary pressers 1 brought into operation at a time when the needles 7 still pursue their normal pressing motions.

When the machine resumes its normal knitting motions, by the needle bar and knock-over bar

coming under control of their normal cams 5 and 9, and the auxiliary pressers 4 being lowered, the sequence of operations is as follows:

4. Mis-pressing rod 20 returns under the action of spring 121 and opens mis-pressing switch 29.

5. Knock-over rod 13 returns under the action of spring 66 and closes knock-over switch 31.

6. Press rod 12 returns under the action of spring 55 and closes the needle-pressing switch 30.

At this phase the relay circuit 27 is still open. Should, however, the rod 20 stick (with the result that the auxiliary pressers are left in the operative position) the mis-pressing switch 29 will be left closed, so operation 5 or 6 will result in the relay circuit 27 being completed and the driving motor 23 being brought to a standstill.

The relay circuit 27 is a low tension circuit supplied by way of a transformer 32 (Figure 1). When it is closed a relay coil 33 is energised thereby to operate the second switch 26 to break circuit 34 and to energise telltale lamp 28. Circuit 34 not only includes the automatic switch 24 but also a coil 35 of a relay switch 36 controlling the current supply to motor 23, so that when circuit 34 is broken and coil 35 is de-energised switch 36 opens.

The switches 29, 30, 31 may be snap-action switches such as micro-switches and suitable arrangements of these switches are shown in Figures 3 to 8.

Following the foregoing description the application of the invention to instruments other than the auxiliary pressers of Patent No. 2,428,514 will present no difficulty to the knitting machine builder. For example, the invention may be applied to ensuring that when transfer or picot points are brought into operation, the cyclic motions of the needles are suitably modified.

In Figures 3 and 4 the mis-pressing switch 29 is actuated through the medium of the auxiliary presser actuating bar 17, and adjusting bolt 37, the bar itself being actuated by bell crank 38, rod 39 and truck lever 40 carrying the truck 18; a spring 140 biasses the truck arm in the cam engaging position.

In Figures 5 and 6 the needle pressing switch 30 is actuated by the control rod 12 through the medium of adjustable lug or arm 41.

In Figures 7 and 8 the knock-over switch 31 is actuated through the intermediary of a cup-shaped member 42 biassed by spring 43 and carried by the shogging rod 13. The arrangement is such that additional movement of the rod 13 is permitted whilst maintaining the switch actuated but without further depressing the switch plunger 44.

In the arrangement just described, the pressing switch 30 and the knock-over switch 31 are in parallel with each other and are in series with the mis-pressing switch 29 and the transformer secondary so as to operate the second switch 26 and warning light 28 through a relay circuit 27.

In an alternative arrangement shown in Fig. 9 the warning lamp 28 is not employed and the mis-pressing switch 29 is in parallel with the needle pressing switch 30 and the knock-over switch 31 and these switches 30 and 31 are in series with a relay switch 126. The correct sequence of operations is as follows:

1. Press rod 12 shogs to modify the pressing movements imparted to the needles and to close needle pressing switch 30.

2. Knock-over rod 13 shogs to modify the movement of the knocking-over bits to close knock-over switch 31.

3. Mis-pressing rod 20 shogs to bring the auxiliary pressers into operation and to open mis-pressing switch 29.

4. Mis-pressing rod 20 returns under the action of spring 21 and closes mis-pressing switch 29.

5. Knock-over rod 13 returns under the action of spring 66 and opens knock-over switch 31.

6. Press rod 12 returns under the action of spring 55 and opens the needle pressing switch 30.

By comparison of this sequence of operations with Figure 9 it will be observed that at no time is the circuit open and hence the relay switch 126 (similar to switch 24, Fig. 1) is not actuated to stop the machine. However, should operations 1 or 2 fail, operation 3 immediately results in the circuit being opened; similarly should operation 4 fail, operations 5 or 6 cause the circuit to be opened.

Having now described and ascertained the nature of our said invention and in what manner the same is to be performed, we hereby declare that what we claim is:

1. In a straight bar knitting machine having knitting elements movable in a normal knitting cycle but also movable in a modified cycle, a mechanism for effecting the change over between the two cycles of movement, instruments movable to occupy, for a period during which the said elements perform their modified cycle of movement, a temporary attitude in which they cooperate with said elements, and control mechanism for producing movement of said instruments into and out of their temporary cooperation; a stop motion including detecting apparatus for detecting an incorrect relationship between the kind of cycle performed by the knitting elements and the attitude of the instruments.

2. Apparatus according to claim 1, wherein the detecting apparatus comprises an electric control circuit for the stop motion and the two control switches in it which are operable in opposite senses, whereof one switch is operable by the change-over mechanism and the other by the control mechanism.

3. In a straight bar knitting machine having knitting elements movable in a normal knitting cycle but also in a modified cycle, a change-over device movable in one sense to produce the change-over from the normal knitting cycle to the modified cycle and in the reverse sense to produce the reverse change, instruments movable to occupy, for a period during which the said knitting elements perform their modified cycle of movements, a temporary attitude in which they cooperate with said elements, and a control device movable in one sense to produce movement of the instruments to cooperating attitude and in the reverse sense to produce movement out of that attitude; a stop motion including means responsive to incorrect relative movement between said devices for stopping the machine.

4. In a straight bar knitting machine having knitting elements movable in a normal knitting cycle but also in a modified cycle, a change-over device movable in one sense to produce the change-over from the normal knitting cycle to the modified cycle and in the reverse sense to produce the reverse change, instruments movable to occupy, for a period during which the said knitting elements perform their modified cycle of movements, a temporary attitude in which they

cooperate with said elements, and a control device movable in one sense, upon movement of the first device to produce change-over to the modified cycle, to produce movement of the instruments to the cooperating attitude and in the reverse sense, upon movement of the first device to produce the change-over to the normal cycle, to produce movement of the instruments out of that attitude; a stop motion including means responsive to the aforesaid movements of either device being incorrect relative to movement of the other device.

5. In a straight bar knitting machine having knitting elements movable in a normal knitting cycle but also in a modified cycle, a change-over device movable in one sense to produce the change-over from the normal knitting cycle to the modified cycle and in the reverse sense to produce the reverse change, instruments movable to occupy, for a period during which the said knitting elements perform their modified cycle of movements, a temporary attitude in which they cooperate with said elements, and a control device movable in one sense, upon movement of the first device to produce change-over to the modified cycle, to produce a movement of the in-

10
15
20
25

struments to the cooperating attitude and in the reverse sense, upon movement of the first device to produce the change-over to the normal cycle, to produce movement of the instrument out of that attitude; a stop motion including a control circuit containing switches, controlled respectively by the two devices, for rendering said circuit operative upon aforesaid movements of either device being incorrect relatively to movement of the other device.
